UNITED STATES PATENT OFFICE.

FRANK FREDRICK GETZE, OF LOS ANGELES, CALIFORNIA.

HASP-LOCK.

SPECIFICATION forming part of Letters Patent No. 531,178, dated December 18, 1894.

Application filed March 22, 1894. Serial No. 504,704. (No model.)

To all whom it may concern:

Be it known that I, FRANK FREDRICK GETZE, a citizen of the United States, residing at Los Angeles, in the county of Los Angeles and State of California, have invented a new and useful Hasp-Lock, of which the following is a specification.

The invention relates to improvements in hasp locks.

10 The object of the present invention is to improve the construction of hasp locks and to provide an efficient one adapted for use on car-doors, ordinary doors, and the like, and capable, when employed on car doors, of being used in connection with the ordinary seal.

15 The invention consists in the construction and novel combination and arrangement of parts hereinafter fully described, illustrated in the accompanying drawings, and pointed out in the claims hereto appended.

20 In the drawings: Figure 1 is a perspective view of a hasp lock constructed in accordance with this invention. Fig. 2 is a plan view, the casing of the lock being shown in section, and the parts being locked. Fig. 3 is a similar view, the parts being unlocked. Fig. 4 is a detail perspective view of the transversely-movable bolt. Fig. 5 is a transverse sectional view.

25 30 Like numerals of reference indicate like parts in all the figures of the drawings.

35 1 designates a hasp, having mounted on its swinging or movable member 2 a rectangular shell or lock-casing 3, which contains a longitudinally-movable bolt 4, and which is secured to the said movable member by pins or the like. Within the casing is arranged a key-stud 5, mounted on the hinged member 2 of the hasp, and located opposite a V-shaped key-engaged recess 6, whereby the bolt is shot by the key in either direction. A series of tumblers 7, which are spring actuated, is arranged adjacent to and resting against the bolt, and provided with recesses 45 or openings for engaging a lug 8 of the bolt. These tumblers operate in the usual manner and are adapted to be engaged by a key to be lifted clear of the lug 8 to permit the bolt to be moved, and by changing the tumblers many 50 varieties of locks and keys may be constructed, as will be readily understood.

The longitudinally-movable bolt 4 is arranged to engage a socket or recess 9, of a transversely-movable bolt 10, which is bifurcated to provide inner and outer arms 11 and 12. The inner arm is located within the lock-casing and operates through an opening 13 thereof. It is guided by a rib 13^a, and is provided with a longitudinal slot 14, to receive a pin or other fastening device for limiting the transverse movement of the bolt 10, which may be raised or moved outward when the longitudinal bolt 4 is retracted.

55 The outer arm 12 is located opposite the staple-opening 15 of the hinged member of the hasp, which opening 15 is adapted to receive a staple 16 of a keeper 17 in the usual manner to permit the outer arm 12 to engage the staple and secure the hasp in the ordinary manner. When the transversely-movable bolt 10 is moved inward into engagement with the staple 16, it is locked in that position by the longitudinal bolt 4, which engages the socket or recess 9 arranged at the top or outer side of the bolt 10.

60 70 75 In order to hold the transverse bolt raised, or in its outward or extended position, a flat friction spring 18 is secured within the casing by means of the pin 19, and this spring engages the inner arm of the transverse bolt 80 with sufficient friction to prevent any accidental inward movement.

75 80 85 When the hasp lock is designed to be used in connection with freight-car doors, an ordinary seal 20 is employed, and the wire 21 thereof is passed through the staple and an opening 22 of a flange 23 at the outer side of the transverse bolt. A key-hole cover may be employed if desired, and this will be found of more service when the hasp lock is employed on car doors, as it is then very much exposed to the weather.

90 95 It will be seen that the hasp lock is simple and comparatively inexpensive in construction, that it is positive and reliable in operation, and that it is adapted for use on car doors, or at any other place where the ordinary hasp is used, and that it is capable of permitting the use of a car seal.

100 Changes in the form, proportion, and the minor details of construction may be resorted to without departing from the principle or

sacrificing any of the advantages of this invention.

What I claim is—

1. The combination of a hasp, a lock mounted thereon and provided at one side with an opening and having a transverse way located at the opening, a transversely movable bolt composed of inner and outer arms, the outer arm being located outside of the lock casing and arranged opposite the hasp opening, and the inner arm being located in said way and guided by the same and having a limited movement, and a longitudinal bolt mounted within the lock casing and adapted to be operated by a key, and arranged to engage the inner arm of the transverse bolt to secure the same against outward movement, substantially as described.
2. The combination with a hasp, of a lock-casing mounted on the hasp, a longitudinal bolt arranged in the casing and adapted to be operated by a key, a transversely - movable bolt having inner and outer arms, the outer arm being arranged opposite the hasp-opening and the inner arm being arranged in the casing and operating through the same and arranged to be engaged by the longitudinal bolt and provided with a slot 14 arranged longitudinally of it, and a pin arranged in the slot and limiting the outward movement of the transverse bolt, substantially as described.
3. The combination with a hasp, of a lock-casing mounted on the hasp, a longitudinal

bolt arranged in the casing and adapted to be operated by a key, a transversely-movable 35 bolt having inner and outer arms, the outer arm being arranged opposite the hasp-opening and the inner arm being guided in the casing and operating through an opening in the same and arranged to be engaged by the 40 longitudinal bolt and provided with a slot 14, a pin arranged in the slot and limiting the outward movement of the transverse bolt, and a flat spring disposed longitudinally of the inner arm of the transverse bolt and connected 45 with the casing and frictionally engaging the transverse bolt, substantially as and for the purpose described.

4. The combination with a hasp, of a lock-casing mounted thereon, a longitudinal bolt 50 arranged within the lock-casing, a transverse bolt having inner and outer arms and provided at its outer side with a flange having an opening, said outer arm being located opposite the hasp-opening and the inner arm 55 being arranged within the casing and adapted to be engaged by the longitudinal bolt, substantially as described.

In testimony that I claim the foregoing as my own I have hereto affixed my signature in 60 the presence of two witnesses.

FRANK FREDRICK GETZE.
